CLAIM

The ornamental design for an electronic device, as shown and described.

DESCRIPTION

FIG. 1 is a front perspective view of an electronic device showing our new design according to a first embodiment;

FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof;
 FIG. 7 is a bottom plan view thereof;
 FIG. 8 is a rear perspective view thereof;
 FIG. 9 is a front perspective view of an electronic device showing our new design according to a second embodiment;
 FIG. 10 is a front elevation view thereof;
 FIG. 11 is a rear elevation view thereof;
 FIG. 12 is a left side elevation view thereof;
 FIG. 13 is a right side elevation view thereof;
 FIG. 14 is a top plan view thereof;
 FIG. 15 is a bottom plan view thereof;
 FIG. 16 is a rear perspective view thereof;
 FIG. 17 is a front perspective view of an electronic device showing our new design according to a third embodiment;
 FIG. 18 is a front elevation view thereof;
 FIG. 19 is a rear elevation view thereof;
 FIG. 20 is a left side elevation view thereof;
 FIG. 21 is a right side elevation view thereof;
 FIG. 22 is a top plan view thereof;
 FIG. 23 is a bottom plan view thereof;
 FIG. 24 is a rear perspective view thereof;
 FIG. 25 is a front perspective view of an electronic device showing our new design according to a fourth embodiment;
 FIG. 26 is a front elevation view thereof;
 FIG. 27 is a rear elevation view thereof;
 FIG. 28 is a left side elevation view thereof;
 FIG. 29 is a right side elevation view thereof;
 FIG. 30 is a top plan view thereof;
 FIG. 31 is a bottom plan view thereof;
 FIG. 32 is a rear perspective view thereof;
 FIG. 33 is a front perspective view of an electronic device showing our new design according to a fifth embodiment;
 FIG. 34 is a front elevation view thereof;
 FIG. 35 is a rear elevation view thereof;
 FIG. 36 is a left side elevation view thereof;
 FIG. 37 is a right side elevation view thereof;
 FIG. 38 is a top plan view thereof;
 FIG. 39 is a bottom plan view thereof;
 FIG. 40 is a rear perspective view thereof;
 FIG. 41 is a front perspective view of an electronic device showing our new design according to a sixth embodiment;
 FIG. 42 is a front elevation view thereof;
 FIG. 43 is a rear elevation view thereof;
 FIG. 44 is a left side elevation view thereof;
 FIG. 45 is a right side elevation view thereof;
 FIG. 46 is a top plan view thereof;
 FIG. 47 is a bottom plan view thereof; and,
 FIG. 48 is a rear perspective view thereof.

The evenly dashed broken lines in the drawings illustrate portions of the electronic device that form no part of the claimed design. The dot-dash broken lines in the drawings define the boundary of the claimed design and form no part thereof.
